US0D1022611S

(12) **United States Design Patent** (10) **Patent No.:** **US D1,022,611 S**
(45) **Date of Patent:** **** Apr. 16, 2024**

(54) **COOLER**

(71) Applicant: **LIFETIME PRODUCTS, INC.**,
Clearfield, UT (US)

(72) Inventor: **Robert A. Astle**, Farmington, UT (US)

(73) Assignee: **LIFETIME PRODUCTS, INC.**,
Clearfield, UT (US)

(**) Term: **15 Years**

(21) Appl. No.: **29/808,444**

(22) Filed: **Sep. 20, 2021**

Related U.S. Application Data

(63) Continuation of application No. 29/713,735, filed on
Nov. 18, 2019, now Pat. No. Des. 942,218.

PRODUCTS, INC.

(57) **CLAIM**

The ornamental design for a cooler, as shown and described.

DESCRIPTION

FIG. 1 is a top, front, right side perspective view of a cooler showing my new design.

FIG. 2 is a bottom, rear, left side view thereof.

FIG. 3 is a front view thereof.

FIG. 4 is a rear view thereof.

FIG. 5 is a left side view thereof.

FIG. 6 is a right side view thereof.

FIG. 7 is a top plan view thereof; and,

FIG. 8 is a bottom plan view thereof.

The broken lines showing the remaining portions of the cooler are for illustrative purposes only and form no part of the claimed design.

1 Claim, 7 Drawing Sheets
